(57) **CLAIM**

The ornamental design for a truck quarter fender fairing, as shown and described.

DESCRIPTION

FIG. 1 is a perspective view of a truck quarter fender fairing of our new design;

FIG. 2 is a perspective view of the quarter fender fairing in isolation;

FIG. 3 is a view of the fairing from the left side of a truck;

FIG. 4 is a top view;

FIG. 5 is a rear view; and,

FIG. 6 is a bottom view.

The front of the truck quarter fender fairing is unornamented.

The broken line showing of a truck fairing, in FIG. 1, depicts environment and is not part of the claimed design.

FIGS. 1-6 illustrate a first embodiment of our novel design suitable for use on the left side of a truck. Our novel design also includes a second embodiment suitable for use on the right side of a truck, which is mirror symmetrical to FIGS. 1-6 and therefore not separately illustrated.
